(57) **CLAIM**

The ornamental design for a cup sleeve, as shown and described.

DESCRIPTION

FIG. 1 is a front, left, top perspective view of a cup sleeve showing my new design;

FIG. 2 is a back, right, bottom perspective view thereof;

FIG. 3 is a back, right, top perspective view thereof;

FIG. 4 is a front elevation view thereof;

FIG. 5 is a back elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is an enlarged view of the encircled portion “10” in FIG. 2;

FIG. 11 is an enlarged view of the encircled portion “11” in FIG. 2; and,

FIG. 12 is an enlarged view of the encircled portion “12” in FIG. 4.

The dot-dot-dash lines shown on the cup sleeve depict stitching, which does form a part of the claimed design.

The equal-length broken lines depict portions of the cup sleeve that form no part of the claimed design.

The dash-dot lines in FIGS. 2, 4, 10, 11 and 12 illustrate the boundaries of the enlarged view indicators and form no part of the claimed design.

1 Claim, 12 Drawing Sheets
